UNITED STATES PATENT OFFICE.

ALEXANDER BOYNTON, OF SAN ANTONIO, TEXAS.

BAILER.

Application filed May 8, 1922. Serial No. 559,364.

To all whom it may concern:

Be it known that I, ALEXANDER BOYNTON, a citizen of the United States, and resident of San Antonio, in the county of Bexar and State of Texas, have invented certain new and useful Improvements in Bailers, of which the following is a specification.

This invention relates to bailers especially adapted for use in oil wells.

10 The invention has for one of its objects the provision of novel means whereby the downward thrust is utilized to introduce the mud or other material into the bailer through the main inlet opening in the lower 15 end of the bailer and incidentally through the openings in the opposite sides of the bailer.

In the practice of the invention, the intake and discharge openings in the opposite 20 sides of the bailer are exposed when the bailer approaches the bottom of the well so as to receive the lighter mud, the heavier mud being introduced into the bailer through the main inlet opening in the lower 25 end thereof.

Further the invention forming the subject matter of this application aims to provide a bailer having means whereby the discharge openings are uncovered simultaneously with the impact of the bailer on the sill of the derrick so that a maximum quantity of material may be discharged on each impact.

Further the invention operates to dump the mud rapidly without removing the bottom, manipulating springs, pins or slots, thus saving a great deal of time in operation and adding greatly to the convenience of operation.

40 In operation the invention forming the subject matter of this application does not depart radically from established practices and consequently it will be favorably received when placed upon the market.

45 A further object is to provide a bailer having oppositely arranged discharge openings, one of the openings being adapted for the reception of a steam or water hose while the other opening is adapted for the discharge of the mud sludge or other collected material and the steam and hot water whereby the steam which is introduced into the bailer for the purpose of loosening and

melting down the mud is discharged out through the other opening along with the 55 mud.

A further object is to provide a bailer which is reliable in use, positive in action, and durable and cheap to manufacture.

Other objects and advantages of the invention will be apparent during the course 60 of the following description.

In the accompanying drawings, forming a part of this application, and in which like numerals are employed to designate like 65 parts throughout the same,

Figure 1 is a side elevation of the improved bailer,

Figure 2 is a side elevation partly in section.

Figure 3 is a vertical longitudinal sectional view through the same,

Figure 4 is a section on line 4-4 of Figure 3.

In the drawing wherein for the purpose 75 of illustration is shown a preferred embodiment of the invention, the numeral 70 designates an inner sleeve which as illustrated in Fig. 2 has its lower end formed with a shoulder 71 with which a valve seat 72 80 contacts. The valve seat 72 is provided with a flap valve 73 which allows mud to enter the bailer and prevents the escape of mud through the lower end thereof at all times.

The bailer bottom is designated by the 85 numeral 74 and is threaded into the inner sleeve 70 and engages the lower side of the valve seat 72 whereby to securely and positively hold the valve seat in position. The lower end of the bailer bottom is exteriorly enlarged to form an annular shoulder 75 which limits the downward movement of the outer sleeve. The interior of the bottom member 74 is flared as indicated at 76 so that the mud will be guided into 90 the bailer when the bailer is thrust downward.

When the bailer is introduced into the well, the thrust of the bailer is utilized as a means for forcing the heavy mud in 100 through the bottom member 74 and through side slots.

As illustrated in Figure 3 an outer sleeve 77 is slidable on the inner sleeve and is formed with a longitudinally extending slot 105 78 which receives a stop screw or pin 79

carried by the inner sleeve. The stop screw or pin 79 serves as a means for limiting the movement of the sleeves with relation to each other and also serves as a positive means for preventing the loss of the inner sleeve. It might be stated that the bushing 86 which is threaded into the forward portion of the outer sleeve contacts with the forward portion of the inner sleeve. It is thus seen that the pin 79 and the exteriorly threaded bushing 86 form a positive means whereby the disconnection of any of the parts is prevented and consequently the bailer may be withdrawn intact from the well.

In carrying out the invention the inner sleeve 70 is provided with two oppositely arranged openings 80 through which light mud is admitted into the bailer and through which all of the mud is discharged when the bailer is withdrawn from the well and thrust upon sill or dumping block. Also the outer sleeve 77 is provided with two oppositely arranged openings 81 adapted for registration with the openings 80 whereby light mud may be admitted to the bailer and whereby all the mud may be discharged. However, the openings 81 are brought into registration with the openings 80 only when the outer sleeve is advanced on the inner sleeve. A coiled spring 82 is confined between the rear end of the inner sleeve and an annular shoulder 83 at the rear end of the outer sleeve and the said coiled spring serves as a means for normally holding the parts in the position illustrated in Figure 3, in which Figure the openings are not in registration. It will be seen that the pin 79 and the slot 78 insure registration of the openings 80 and 81 when the outer sleeve 77 is advanced.

When the bailer is introduced into the well it passes through the light mud and when the bottom section 74 encounters the heavy mud, the mud passes up past the valve 73 and into the bailer. When the bailer encounters the heavy mud the lighter mud is passed through the openings 80 and 81 as at this period of the operation, the outer sleeve 77 has advanced against the tension of the coiled spring 82. The lighter mud which surrounds the bailer and is under a considerable pressure rushes in through the aligned openings 80 and 81 and thereby partly fills the bailer. When the bailer is filled it is withdrawn to the surface and as the same is brought down on the sill of the derrick, the openings 80 and 81 are brought into registration simultaneously with the impact so that a maximum quantity of mud is discharged.

With reference to the foregoing description, it will be seen that a bailer constructed in accordance with this invention does not involve a radical departure in operation

from bailers now in use and consequently the bailer will not be met with prejudice when placed upon the market.

In dumping the material may be rapidly discharged from the bailer without first removing springs, bailer bottoms, pins and the like and without inconvenience on the part of the operator or attendant.

If the mud will not readily discharge itself through the aligned openings 80 and 81 a steam or water hose may be introduced into the bailer through one of the openings and the stiff mud may be readily melted down and discharged through the opposite opening without the returning steam being discharged upon the operator's hands, as is the case when only one opening is available for this purpose.

Further, it will be seen that the bailer bottom 74 is practically unlosable because the inner sleeve which contains the valve cannot be lost unless the outer sleeve bushing should be stripped out of its threads or be backed off, all of which is practically impossible, because of lock pin 85. The weight of the bailer and the contents of the same is not sufficient to strip the threads from the outer sleeve bushing 86 and the forward portion of the outer sleeve 77 and further the elasticity of the sand line is sufficient to effectively absorb violent jerks and pulls. Also it will be seen that the bushing 86 is non-rotatably connected to the outer sleeve by means of pins or fastening devices 85.

Figure 3 illustrates that the lower end of the bushing is formed with oppositely located slots 87 to receive a tool or piece of metal employed for threading the bushing into the sleeve 77.

It is to be understood that the form of the invention herewith shown and described is to be taken as a preferred example of the same and that such minor changes in arrangement and construction of parts may be made as will remain within the spirit of the invention and the scope of what is claimed.

Having thus described the invention, what I claim is:—

1. A bailer comprising an outer sleeve, an inner sleeve slidably connected thereto, the inner and outer sleeves being provided with openings adapted for registration, means whereby to hold the inner and outer sleeves against rotation with relation to each other, said means being adapted to limit the longitudinal movement of said sleeves with relation to each other, a spring confined between the rear portions of said inner and outer sleeves, and urging the inner sleeve to its advanced position with relation to the outer sleeve, and an inlet valve carried by the forward portion of the inner sleeve.

2. A bailer comprising an outer sleeve, an inner sleeve slidably connected thereto, the

- inner and outer sleeves being provided with openings adapted for registration, means whereby to hold the inner and outer sleeves against rotation with relation to each other, said means being adapted to limit the longitudinal movement of said sleeves with relation to each other, a spring confined between the rear portions of said inner and outer sleeves and urging the inner sleeve to its advanced position with relation to the outer sleeve, an inlet valve carried by the forward portion of the inner sleeve, and a bushing threaded on the forward portion of said outer sleeve and limiting the forward movement of the inner sleeve.
3. A bailer comprising an outer sleeve, an inner sleeve slidably connected thereto, the inner and outer sleeves being provided with openings adapted for registration, means whereby to hold the inner and outer sleeves against rotation with relation to each other, said means being adapted to limit the longitudinal movement of said sleeves with relation to each other, a spring confined between the rear portions of said inner and outer sleeves and urging the inner sleeve to its advanced position with relation to the outer sleeve, an inlet valve carried by the forward portion of the inner sleeve, a bushing threaded on the forward portion of said outer sleeve and limiting the forward movement of the inner sleeve, and a bailer bottom threaded into the forward portion of the inner sleeve and engaging said valve for holding the same in a set position.
4. A bailer comprising an outer sleeve, an inner sleeve slidably connected thereto, the inner and outer sleeves being provided with openings adapted for registration, means whereby to hold the inner and outer sleeves against rotation with relation to each other, said means being adapted to limit the longitudinal movement of said sleeves with relation to each other, a spring confined between the rear portions of said inner and outer sleeves and urging the inner sleeve to its advanced position with relation to the outer sleeve, an inlet valve carried by the forward portion of the inner sleeve, a bushing threaded on the forward portion of said outer sleeve and limiting the forward movement of the inner sleeve, a bailer bottom threaded into the forward portion of the inner sleeve and engaging said valve for holding the same in a set position, said bailer bottom having its forward portion flared and formed with a shoulder for limiting the forward movement of the outer sleeve.
5. A bailer comprising inner and outer sleeves having material admitting and discharge openings, an inlet valve controlling the admission of material through the forward ends of the sleeves, and a contact member connected to one of the sleeves and engaging and holding said valve in place and having a stop member limiting the sliding movement of the other sleeve.
6. A bailer comprising inner and outer sleeves having material admitting and discharge openings, an inlet valve controlling the admission of material through the forward ends of said sleeves, a contact member connected to one of the sleeves and engaging and holding said valve in place and having a stop limiting the sliding movement of the other sleeve, said contact member being adapted for the admission of material and extending beyond the forward ends of said sleeves.
7. A bailer comprising inner and outer sleeves having material admitting and discharge openings, an inlet valve controlling the admission of material through the forward ends of the sleeves, a contact member connected to one of the sleeves and holding said valve in place, and a spring urging the sleeves to their material retaining positions.
8. A bailer comprising inner and outer sleeves having material admitting and discharge openings, an inlet valve controlling the admission of material through the forward ends of the sleeves, and a contact member connected to one of the sleeves and being hollow for the passage of material, and means slidably connecting the sleeves and limiting the movement of the same with relation to each other, there being means to yieldingly urge the sleeves to their material retaining positions and to permit of the registration of said discharge openings.
9. A bailer comprising inner and outer sleeves having material admitting and discharge openings, an inlet valve controlling the admission of material through the forward ends of the sleeves, and yieldable means for urging the sleeves to their material retaining position.

ALEXANDER BOYNTON.
